UNITED STATES PATENT OFFICE

EUGENE BOOTZ, OF DENVER, COLORADO

LIFTING JACK

Application filed March 26, 1929. Serial No. 349,934.

This invention relates to improvements in lifting jacks and has reference more particularly to a lifting jack of the type employed in connection with automobiles and other vehicles.

It is customary at the present time to attach to the front and rear ends of automobiles, bumpers which project a considerable distance to the front of the front axle and to rear of the rear axle. These bumpers form obstructions which make it difficult to place an ordinary lifting jack under the axle for the purpose of raising the axle whenever this becomes necessary. Due to the great distance from the bumpers to the axles, it is necessary in order to place an ordinary jack under the axles, to lie flat on the ground, as only in this manner can the jack be placed and operated. In order to overcome this objectionable feature, various jacks have been invented which are operated by means of long handles that make it possible to put the jack in place and to operate it from a position in front of the front bumper or in the rear of the rear bumper.

It is the object of this invention to produce a jack of a simple and substantial construction that shall be so made that when it is in proper position to be inserted under the axle of an automobile, it will be extended so that it can be shoved into place and which is operated by means of a fall and tackle, the rope forming the fall being of such length that the person operating the jack can stand in a comfortable position while pulling the same.

This invention, briefly described, comprises a base which is adapted to rest upon the ground and which has an upwardly extending tubular post within which is slidably arranged a sleeve within which a bar is telescopically mounted. The upper end of this bar is provided with a lifting head and the upper end of the sleeve is provided with a casting having an opening through which the bar projects. This casting has a pawl which serves to hold the bar in extended position. The casting at the upper end of the sleeve is moved towards and away from the base by means comprising two lazy tong structures one of these tongs being located on each side

of the tubular member and has one corner pivotally connected to the base, while the other is pivoted to the casting on the upper end of the sleeve. The end links of the lazy tongs are connected by means of pulley blocks, each of which is provided with two or more pulleys. These pulleys are interconnected by means of a rope in the manner of a fall and tackle so that when force is applied to the rope, the lazy tong structures will be collapsed thereby spreading the vertices and raising the sleeve upwardly in the tubular member. Means is also provided for holding the lazy tong structures against both upward and downward movement and for latching the rope so as to hold the jack in any desired position.

Having thus briefly described the invention, the same will now be described in detail, and reference for this purpose will be had to the accompanying drawings, in which the preferred embodiment has been illustrated, and in which:

Fig. 1 is a side elevation of the improved jack showing the lazy tong device in extended position;

Fig. 2 is a top plan view of the jack parts being shown in section;

Fig. 3 is a section taken on line 3-3, Fig. 1;

Fig. 4 is a section taken on line 4-4, Fig. 1;

Fig. 5 is a section to a somewhat enlarged scale, taken on line 5-5, Fig. 2; and

Fig. 6 is a section taken on line 6-6, Fig. 5; and

Fig. 7 is a section taken on line 7-7, Fig. 5.

In the drawings reference numeral 1 designates a base which is adapted to rest upon the ground, or any other supporting surface. This base has been shown as of rectangular shape and considerably longer than it is wide. A tubular post 2 extends upwardly from the center of the base and is preferably formed integral therewith. On each side of post 2 are two upwardly extending spaced lugs 3, which are provided with perforations for the rivets or bolts 4 that form the pivot for the links of the lazy tong devices which are employed for raising and lowering the jack.

and which will be hereinafter described. Located within the post 2 is a sleeve 5, which is provided at its front and rear with slots 6 whose purpose will hereinafter be explained. Secured to the upper end of sleeve 5 and preferably formed integral therewith is a head 7 which is provided with an opening that forms a continuation of the opening in sleeve 5. A bar 8 which is provided on one side with a plurality of ratchet teeth 9 is telescopically mounted in sleeve 5. The upper end of bar 8 is provided with a lifting head 10, that is adapted to engage the automobile axle or the under surface of any thing that is to be lifted by means of the jack. The head 7 is provided on opposite sides with downwardly extending ears or lugs 11 corresponding to lugs 3 on the base. These lugs are provided with openings for the reception of pivot pins 12 by means of which the links of the lazy tong devices are secured to the head. A pin 13 extends from one side of head 7 to the other and forms a pivot for a pawl 14 which is provided with two handles 15 that straddle the tubular member 5 in the manner shown in Figs. 5 and 6. When the bar 8 is to be lowered within the tubular member, handles 15 are raised upwardly so as to release the pawl. The lower end of bar 8 is split and is provided with a small pulley 16 that is attached to it by means of a pivot pin 17. A cord or steel cable 18 has one end anchored to the head 7 at 19 and extends downwardly around the pulley 17 and thence upwardly and passes over a pulley 20 pivotally attached to head 7 in the manner shown in Fig. 5. When tension is applied to this cord of rope in the direction of the arrow in Fig. 5, the bar 8 may be moved upwardly within the sleeve and in this manner the height of the lifting head 10 can be adjusted to fit the height of the axle or other article that is to be lifted. For the purpose of accommodating the cord 18, post 2 is provided with slots 21 in the manner shown in Fig. 5.

The mechanism for operating the jack will now be described. This mechanism consists of two lazy tong structures, each of which consists of two groups "A" and "B" of links 22, which are pivotally connected at their middle points as indicated by reference numeral 23. The ends of one of these pairs of links are pivotally attached respectively to the base and to head 7 by means of pivot pins 4 and 12. Pivotally attached to pins 4 and 12, are short links 24 whose other ends are pivoted at 25 to a pulley block 26. This block is provided with transverse members 27 that are spaced apart sufficiently to receive the pulleys 28. A bolt 29 serves as the pivot about which the pulleys rotate. The pulley block 26 is provided with a handle or loop 30 for convenience in extending the lazy tong. It will be seen from Figs. 2, 3 and 4 that there are two lazy tong assemblies of

identical construction, one located on each side of the tubular member 2, but as these are exactly alike, the same reference numerals are employed to indicate the corresponding elements of each of these assemblies. Pivots 32 are provided at the free ends of the links comprising pair "A" and 31, whose outer ends are connected by means of pivots 32 with the pulley block 33. Pulley block 33 is substantially identical with block 26 and differs therefrom only in minor details and will therefore not be described, except for the purpose of calling the attention to the differences. From Fig. 3 it will be seen that pulley block 33 is provided with an upwardly extending lug or ear 34 through which the pivot pin 32 extends. A pulley 35 is pivoted on the pivot pin 32 adjacent one side of the pulley block. Both of the pulley blocks 26 and 33 are provided on each side with inwardly extending fingers 36, which serve as guides for the pivot pins 37 that connect the ends of the auxiliary links 38. The other ends of these links are pivoted at 39 and 40 to links 22 and to the links 22 that are pivoted to the base and to the head 7. A rope 41 forms the fall of the tackle and when force is applied to the free end of this rope in the direction of arrow 42, the pulley blocks will be moved towards each other, thereby collapsing the lazy tong devices. It is obvious from an inspection of Fig. 1 that pivots 4 and 12 move apart when the lazy tong assemblies are collapsed and move towards each other when the lazy tong assemblies are extended. And it is also evident that the distance which the pulley blocks 26 and 33 must approach each other for a given variation in the distance between 4 and 12 varies directly with the number of link assemblies employed in the lazy tong devices; so that by increasing the number of these link assemblies, a multiplication of force is thereby obtained. The power of the jack with a certain number of pulleys can therefore be varied by varying the number of link assemblies. It is also evident that as the link assemblies approach collapsed position, their toggle actions will increase as this varies with the size of the angle designated by "W".

The operation of the jack is as follows: When the jack is to be used, it is extended until it occupies the position shown in Fig. 1. This brings the head 7 downwardly towards the base. The jack is now inserted and put in place underneath the axle or other object to be lifted. The operator then pulls cord 18, thereby raising the bar 8 upwardly until the head 10 engages the object to be lifted. Force is now exerted on the free end of rope 41, thereby moving the pulley blocks 26 and 33 towards each other, whereby the head 7 and bar 8 with its attached head 10 will be moved upwardly, so as to lift the automobile axle or other object. After the

object has been raised to the extent desired, rope 42 may be clamped in the notch 43, which serves to latch the rope although this is not as a rule necessary when the lazy tong devices are entirely collapsed as the friction of the parts is sufficient to maintain the parts in collapsed position with any ordinary load.

In the above description a specific embodiment of the invention has been described in order to illustrate the construction. It is my intention, however, to construct the jack entirely from soft steel bars and plates that can be readily shaped by means of dies instead of using castings and to arrange the pulleys 28 so that they will rotate about horizontal instead of about vertical axes. It is also evident that the end links 24 and 31 may have common pivots 25 and 32 for each pair of links instead of having two spaced pivots 25 and two spaced pivots 32. Handles 30 can also be replaced by chain loops.

From the above it will be seen that I have produced a lifting jack of a simple construction that is especially well adapted for use in connection with automobiles as it can be readily put in place and removed and which can be cheaply constructed, owing to the fact that most of the parts are duplicates.

Having described the invention what is claimed as new is:

1. A lifting jack comprising, in combination, a base having a standard projecting from one side thereof, a bar slideable on the standard, a lifting head secured to the upper end of the bar, a lazy tong structure comprising a plurality of sets of links pivotally connected at their centers and having the adjacent ends of each pair pivotally connected, the links of each end pair being pivotally connected to the ends of shorter links, pulley blocks connecting the other ends of the shorter links, the pivot between one of the long links and one of the shorter links being connected with the base, the opposite corresponding pivot of the lazy tong being connected with the lifting head and a rope cooperating with the pulley blocks to form with the latter a fall and tackle.

2. A lifting jack comprising, in combination, a base adapted to rest upon a supporting surface, a lifting head slidably connected with the base so that it may move towards and away from the latter, and means for moving the head with respect to the base, said means comprising a lazy tong composed of a plurality of sections of crossed links, the end of one link of one pair of links being connected with the base and the end of the other link of the pair being connected with the head whereby when the tong is extended the head and base will approach each other and when the tong is shortened the head will be moved away from the base and means comprising a fall and tackle device for collapsing the tong.

3. A lifting jack comprising, in combination, a base adapted to rest upon a supporting surface, a lifting head slidably connected with the base so that it may move towards and away from the latter, and means for moving the head with respect to the base, said means comprising a lazy tong composed of a plurality of sections of crossed links, the end of one link of one pair of links being connected with the base and the end of the other link of the pair being connected with the head whereby when the tong is extended the head and base will approach each other and when the tong is shortened the head will be moved away from the base, a plurality of pulleys attached to the links at the opposite ends of the tong and a rope encircling the pulleys to form a fall and tackle.

In testimony whereof I affix my signature.

EUGENE BOOTZ.
